[57] CLAIM

The ornamental design for stand for hanging plants, as shown and described.

DESCRIPTION

FIG. 1 is a front elevational view of a stand for hanging plants showing my new design;

FIG. 2 is a left side elevational view thereof;

FIG. 3 is a right side elevational view thereof;

FIG. 4 is a rear elevational view thereof;

FIG. 5 is a top plan view thereof;

FIG. 6 is a bottom plan view thereof;

FIG. 7 is a perspective view thereof, the broken lines shown are for illustrative purposes only and form no part of the claimed design; and,

FIG. 8 is a perspective view of a second embodiment of FIG. 1, it being understood that the undisclosed rear, side and bottom are basically the same as in the first embodiment.
